WRITING INSTRUMENT

Herman C. Frentzel, Milwaukee, Wis., assignor to
The Parker Pen Company, Janesville, Wis., a
corporation of Wisconsin

Application November 15, 1945, Serial No. 628,769

4 Claims. (Cl. 120—42.03)

1

This invention relates to fountain pens of the ball-point type and has to do more especially with a novel projecting-retracting mechanism whereby the writing point may alternately be projected out of and retracted back into the barrel of the instrument.

One of the objects of my invention is to provide in a ball-point fountain pen a projecting-retracting mechanism of simple and rugged construction which is economical to manufacture and unlikely to get out of order.

By virtue of being inherently leak-proof, a ball-point fountain pen can safely be carried point down, and the detachable cap usually provided on pocket fountain pens can be dispensed with. However, there is always a modicum of ink on the exposed surface of the ball point, and unless some means be provided for retracting the point into the barrel it always is possible that one's clothing may become soiled upon pocketing the pen.

It is believed that the majority of owners of ball-point fountain pens equipped with projecting-retracting mechanisms are not disposed to be negligent about retracting the writing point, but there are some who may at times be forgetful and it is an important object of this invention to provide a projecting-retracting mechanism which will automatically bring about retraction of the writing point in response to the action involved in using the pen clip in the normal manner.

My invention is characterized in that the latch which releasably holds the writing point in projected position is so connected with the pocket clip that lifting the free end of the clip away from the barrel, as is necessarily done in securing the clip to the pocket, is effective to release the projecting-retracting mechanism and thus bring about retraction of the writing point into the barrel.

Other objects and advantages of my invention will be apparent from the detailed description which follows.

In the drawing:

Figure 1 is an elevational view of a ball-point pen in accordance with a preferred embodiment of the invention—the ball point being in retracted position;

Fig. 2 is a view, partly in section and partly in elevation, taken at right angles to Fig. 1 and showing the projecting-retracting mechanism in retracted position;

Fig. 3 is a longitudinal sectional view of the same instrument;

2

Fig. 4 is a transverse sectional view taken along line 4—4 of Fig. 2;

Fig. 5 is a transverse sectional view taken along line 5—5 of Fig. 2; and

Fig. 6 is a fragmentary view taken along line 6—6 of Fig. 2.

The assemblage illustrated comprises an elongate barrel 1 consisting of a tubular portion 2 to the front end of which is detachably connected a tapered tip member 3. Disposed within the barrel is a ball-and-cartridge unit 4 comprising a tubular ink reservoir 5, an ink feed tube 6, and a writing ball 7—the latter being rotatably seated in an adapter 8 which is secured to the front end of feed tube 6. Within the reservoir there may be provided a metal ball 9 which has a close running fit in the bore of the reservoir and serves as a seal to prevent escape of ink from the reservoir and as an auxiliary weight for urging the ink forwardly toward the ball point.

The ball-and-cartridge unit 4 is freely reciprocable lengthwise in the barrel and is continuously urged rearwardly by a coil spring 10. Said unit can be removed for replacement by unscrewing tip member 3 from the tubular portion 2.

A plunger 11 connected to the rear end of ball-and-cartridge unit 4 is reciprocable lengthwise and projects from the rear end of the barrel to form a manually operable pushbutton 11a. Plunger 11 is drilled to provide a vent orifice 12 of smaller diameter which serves to connect the interior of the ink reservoir with the external atmosphere. This is necessary in order to prevent creation of a vacuum within the reservoir such as might prevent feeding out of the ink.

Depression of pushbutton 11a is effective to project both the plunger and ball-and-cartridge unit forwardly against the opposition of spring 10 to the position shown in Fig. 3 wherein the ball point 7 is situated externally of the barrel in writing position.

A lengthwise extending rectangular slot-like opening 13 is provided in the tubular portion 2 of the barrel for the reception of an assembly 45 comprising a pocket clip 14, a latch member 15 and a leaf spring 16, which are secured together at one end by means of a screw 17—said leaf spring 16 being clamped between adjacent ends of pocket clip 14 and latch member 15.

Pocket clip 14 is of the conventional variety comprising an elongate arm anchored at one end and having a free end 14a which is designed to grippingly engage the front-piece of a pocket. As is ordinarily the case, said free end 14a normally bears against the barrel of the instrument under

spring pressure and can be forced away from the barrel to permit insertion of a pocket front-piece.

Latch member 15 is an elongate metal arm, the free end of which is adapted to engage a shoulder 18 on plunger 11 when said plunger is in its retracted position, as depicted in Fig. 2; and it is further adapted to engage a second shoulder 19 on said plunger 11, as shown in Fig. 3, for latching retaining said plunger and said ball-and-cartridge unit in their forward positions as per Fig. 3.

Latch member 15 automatically engages shoulder 19 when the plunger is moved forwardly by depressing pushbutton 11a, and it is operable to disengage said shoulder 19 in response to an outward pull on the free end 14a of pocket clip 14.

Members 14 and 15 are so shaped that they jointly form a recess or groove 20 which is proportioned to embrace the shell of tubular portion 2 at the rear end of slot 13. This engagement affords a pivotal anchorage about which the assembly comprising members 14 and 15 is rotatable, whereby latch member 15 is operable to engage and disengage shoulder 19.

It will be apparent from the foregoing description that the pen structure illustrated is so designed that when the free end 14a of the pocket clip is lifted from the barrel, as in securing the instrument to one's pocket, latch member 15 is rotated about its pivotal anchorage sufficiently to disengage its free end from shoulder 19, thus enabling plunger 11 and the ball-and-cartridge unit 4 to be retracted by spring 10, as depicted in Figs. 1 and 2.

It will be self-evident that there are various modifications and alternative embodiments within the scope and purview of my inventive concept, and I do not wish to be limited except by terms of the appended claims.

I claim:

1. A ball-point writing instrument comprising a barrel, a ball-and-cartridge unit disposed in said barrel and reciprocable lengthwise thereof, said unit comprising an ink reservoir and a writing ball, mechanism for propelling said unit forwardly in said barrel for projecting said writing ball outwardly of the barrel into writing position, a spring for retracting said unit, said mechanism comprising a plunger situated in said barrel at the rear of said unit and reciprocable lengthwise of the barrel, said plunger projecting out of the rear end of said barrel to form a manually operable pushbutton, a latch comprising an arm disposed within said barrel adjacent said plunger and pivotally anchored at one end, the free end of said arm extending forwardly lengthwise of the barrel and positioned to engage a shoulder on said plunger for latching said plunger in its forward position, a spring continuously urging the free end of said arm toward said plunger, a pocket clip mounted exteriorly of said barrel and comprising a second arm pivotally anchored at one end and extending forwardly lengthwise of the barrel, and a connection between said second arm and said first arm for effecting simultaneous rotation of said arms about their pivotal centers whereby a predetermined movement of the free end of said first-mentioned arm about its pivotal center in a direction away from said barrel is effective to unlatch said plunger.

2. A ball-point writing instrument comprising a barrel, a ball-and-cartridge unit disposed in

said barrel and reciprocable lengthwise thereof, said unit comprising an ink reservoir and a writing ball, mechanism for propelling said unit forwardly in said barrel for projecting said writing ball outwardly of the barrel into writing position, a spring for retracting said unit, said mechanism comprising a plunger situated in said barrel at the rear of said unit and reciprocable lengthwise of the barrel, said plunger projecting out of the rear end of said barrel to form a manually operable pushbutton, and an assemblage comprising a first arm, a second arm and an arm-actuating spring, said arms being connected together at one end with one end of said arm-actuating spring clamped therebetween, the interconnected ends of said arms forming, jointly, a groove engaging said barrel to effect a pivotal anchorage for said arms, the other end of said arm-actuating spring being engaged by said barrel, said arm-actuating spring being operative continuously to bias said arms about their pivotal anchorage in such direction that the free end of said first arm is pressed against said plunger while the free end of said second arm is urged toward said barrel, said plunger having a shoulder engageable by said first arm to latch said plunger in its forward position, said second arm constituting a pocket clip.

3. A writing instrument comprising a barrel, a unit slidably mounted in said barrel and including a writing point at the forward end of said unit adapted to be projected and retracted through the adjacent forward end of said barrel,

35 spring means constantly urging said unit toward retracted position wherein said writing point is concealed in said barrel, means for propelling said unit to project said writing point from said barrel, an elongated lever arm positioned in the barrel, means for swingably mounting said arm at one end on the barrel, said arm having its free end positioned to move into latching engagement with said unit for retaining the unit in projected position, means urging the free end of

40 said arm into latching position, and an elongated pocket clip positioned outside the barrel and rigidly secured at one end to the mounted end of said arm, the connection between said arm and clip extending through the barrel, said clip, an outward movement thereof, being effective for moving the free end of said arm out of latching position.

4. A writing instrument comprising a barrel, a unit slidably mounted in said barrel and including a writing point at the forward end of said unit adapted to be projected and retracted through the adjacent forward end of said barrel, spring means constantly urging said unit toward retracted position wherein said writing point is concealed in said barrel, means for propelling said unit to project said writing point from said barrel, an elongated lever arm positioned in the barrel, means for swingably mounting said arm at one end on the barrel, said arm having its free end positioned to move into latching engagement with said unit for retaining the unit in projected position, the free end of said arm being movable to a position further inwardly of the barrel than the mounted end thereof, means urging the free end of said arm into latching position, and an elongated pocket clip positioned outside the barrel and rigidly secured at one end to the mounted end of said arm, the connection between said arm and clip extending through the barrel, said

55 50 55 60 65 70 75 80 85 90 95 100

clip, on outward movement thereof, being effective for moving the free end of said arm out of latching position.
